Atty.

UNITED STATES PATENT OFFICE.

LAWRENCE W. BIEKER, OF HAMMOND, INDIANA, ASSIGNOR TO AMERICAN STEEL FOUNDRIES, OF CHICAGO, ILLINOIS, A CORPORATION OF NEW JERSEY.

SLACK-ADJUSTER MECHANISM.

Application filed July 3, 1922. Serial No. 572,372.

To all whom it may concern:

Be it known that I, LAWRENCE W. BIEKER, a citizen of the United States, residing at Hammond, in the county of Lake 5 and State of Indiana, have invented certain new and useful Improvements in Slack-Adjuster Mechanism, of which the following is a specification.

This invention relates to slack adjuster 10 mechanism which is adapted for use particularly in connection with brake riggings.

The object of this invention is to provide slack adjuster mechanism having relatively few parts, all of which are simple, are easily 15 and simply assembled and which cooperate in a manner to meet all of the requirements for the intended use.

This and other objects are accomplished by means of the arrangement disclosed on 20 the accompanying sheet of drawings, in which—

Figure 1 is a top plan view of an adjuster block with the arms thereof bent inwardly toward each other for facilitating application to an associated member of the slack 25 adjuster;

Figure 2 is a side elevation of the block shown in Figure 1;

Figure 3 is a top plan view of an adjuster 30 jaw showing the method of application of the adjuster block thereto;

Figure 4 is a top plan view of the slack 35 adjuster showing the arms of the adjuster block spread outwardly into their normal positions in which their flanges cooperate to guidedly maintain the block in operative position with respect to the jaw; and

Figure 5 is a sectional view taken in the 40 plane of line 5—5 of Figure 4.

The various novel features of the invention will be apparent from the following description and drawings and will be particularly pointed out in the appended claims.

Referring to the figures of the drawings, 45 it will be noted that the slack adjuster includes a relatively movable member 10 having a jaw portion 11 in the form of a closed loop having sides 12. An adjuster block 13 is mounted within the jaw portion 11 of the member 10 and has two sets of flanges 14 and 15 which embrace the edges of the sides 12 for retaining the adjuster block within 50 the jaw and for guiding the relative move-

ments between the jaw member 11 and the 55 block member 13.

Referring particularly to Figures 1 and 2, it will be noted that the adjuster block 13 is a single piece and that the flanges 14 taper lengthwise of the block, while the 60 flanges 15 are of substantially the same width throughout the length of the block. Also it will be noted that the flanges 14 do not extend the full length of the block 13 while the flanges 15 do. The arms 16 of 65 the block, as shown in Figure 1, are bent inwardly toward each other so that the outer edges 17 thereof extend in the same straight line as the shoulders 18 at the rear of the members 13. The arms 16 are bent 70 inwardly in this manner to facilitate the application of the block 13 to the jaw 11, the application being shown particularly in Figure 3, in which it will be noted that the tapering flanges 14 are passed between the 75 sides 12 of the jaw 11 until the flanges 15 engage the said sides 12, whereupon the arms 16 of the block 13 may be spread apart as shown in Figure 4, in which position adjacent sides of flanges 14 and 15 engage the 80 sides 12 of the jaw 11 for maintaining such parts in the proper cooperative relationship.

After the adjuster block is placed within the jaw, as shown in Figure 4, the adjusting 85 bolt 19 is passed through one end wall of the jaw 11, if it has not already been passed therethrough, and the inner end passed into the pocket 20 of the block 13 and into operative engagement with that end of the 90 block so that if the adjusting bolt 19 is rotated in one direction the block 13 and jaw 11 will have one relative movement, and if rotated in the opposite direction will have an opposite relative movement for the purpose of regulating the amount of slack in 95 the system of brakes.

It will be understood that a brake lever fulcrum pin will be received in the bifurcations at the ends of the block arms 16, a 100 brake lever fulcrumed on said pin and locking keys extend through the openings 21 for locking the fulcrum pin in position. The lever fulcrum pin and the brake lever, however, have not been shown, as they form no 105 part of the present invention.

This slack adjuster comprises a plurality of relatively simple parts which are readily

and simply assembled and relatively adjustable for regulating or adjusting the slack in the brake mechanism.

It is my intention to cover all modifications of the invention falling within the spirit and scope of the following claims.

I claim:

1. A slack adjuster including, in combination, an adjuster jaw, and an adjuster block 10 adjustably and guidedly mounted in said jaw and having flanges which are movable into one position to permit said block to be applied to said jaw and movable into another position after being applied to said jaw to 15 retain said block therein.
2. A slack adjuster including, in combination, an adjuster jaw, and an adjuster block having arms with flanges which cooperate with said jaw for maintaining said block in 20 position with respect to said jaw, said arms being movable into one position to permit passage of one of said flanges during the application of said block to said jaw and said arms being movable into another position 25 to place the flanges into cooperative association with said jaw.
3. A slack adjuster including, in combination, an adjuster jaw, and an adjuster block relatively adjustable and guidedly mounted 30 in said jaw, said block having spaced arms with flanges, the flanges on one of said arms

extending substantially the length of that arm and the flanges on the other arm being of less length, said arms being movable in one direction to permit the passage of the 35 shorter flanges between portions of the jaw member, whereupon the arms may be moved in another direction to place both sets of flanges into operative association with said jaw member for retaining the block operatively within the latter.

4. A slack adjuster including, in combination, an adjuster jaw, and an adjuster block relatively adjustable and guidedly mounted in said jaw, said block having spaced arms 40 with flanges, one of the flanges on one of said arms extending substantially the length thereof and another of said flanges on the other arm being of less length, said arms being movable in one direction to permit the 45 passage of the shorter flange between portions of the jaw member, whereupon the arms may be moved in another direction to place the flanges into operative association with said jaw member for retaining the 50 block operatively within the latter, and means for relatively adjusting said block and jaw member for varying the slack.

Signed at Hammond, Indiana, this 22nd day of June, 1922.

LAWRENCE W. BIEKER.
